Primary Examiner — Rhea Shields(74) *Attorney, Agent, or Firm* — McNees Wallace & Nurick LLC(57) **CLAIM**

The ornamental design for a remote control (wireless), as shown and described.

DESCRIPTION

1.1 is a perspective view of a remote control (wireless), showing the design;
 1.2 is a front view of the remote control (wireless) of 1.1;
 1.3 is a rear view of the remote control (wireless) of 1.1;
 1.4 is a right view of the remote control (wireless) of 1.1;
 1.5 is a left view of the remote control (wireless) of 1.1;
 1.6 is a top view of the remote control (wireless) of 1.1; and
 1.7 is a bottom view of the remote control (wireless) of 1.1.
 In the reproductions, the broken lines are for the purpose of illustrating environment only and form no part of the claimed design.
